FLUID FRICTION REDUCER

Paul Kollsman, New York, N. Y.

Application June 27, 1945, Serial No. 601,905

3. Claims (Ch. 886, p. 3)

This invention relates to means for reducing frictional resistance resulting from relative movement between a solid and a liquid.

This invention relates to means for reducing frictional resistance resulting from relative movement between solid and fluid bodies.

One object of the invention is the provision of means for reducing the relative speed of movement between solid and fluid bodies without reducing the absolute speed of movement of the bodies.

Another object of the invention is the reduction of speed of relative movement between fluid and solid bodies by the positioning of a freely movable member in the fluid medium adjacent to the solid with which it has relative movement.

Another object of the invention is to reduce the frictional resistance to relative rotation of a solid surface and a fluid medium by the positioning of a freely rotatable element or elements in the fluid medium adjacent to the solid surface.

Other objects and features of the invention will be readily apparent to those skilled in the art from the specification and appended drawings illustrating certain preferred embodiments in which:

Figure 1 is a transverse sectional view through a liquid piston-type gas compressor utilizing a form of frictional loss reducer according to the present invention.

Figure 2 is a detailed sectional view on line II-II of Figure 1.

Figure 3 is a detailed sectional view on the line III-III of Figure 1.

Figure 4 is a detailed sectional view on the line IV-IV of Figure 1.

Figure 5 is a sectional view on line V—V of Figure 1.

Figure 1.
In the modification of the invention shown in

Figures 1 through 5, there is provided an annular cup shaped rotor 1 integral with a hub 2 mounted upon a rotatable shaft 3. The rotor 1 is divided by a plurality of curved radial vanes 4 into a plurality of individual peripheral pockets 5, each of the pockets 5 being provided 5 being provided at its bottom surface with a pair of ports or openings 6. The rotor 1 is disposed within a casing 7 forming an elliptically shaped inner chamber shown in Figure 1. The casing chamber closely approaches the rotor 1 at the two sides and is spaced from the rotor at the top and bottom. There is provided an inlet port 8 connected through passages 9 and 11 with ports 12 communicating with the opening 6 in the bottom of the pockets 5. The outlet 13 is connected through passages 14 and 15 with ports 16 communicating with the openings 6 of pockets 5.

The compressor so far described is convenient.

2

tional and its operation well known. A supply of liquid such as water is placed within the chamber 7 and the shaft 3 driven by a motor or other device to rotate the rotor 1. This results in a rotation of the liquid within the container 7 in an elliptical path with the liquid filling the pockets 5 at the side of the chamber and being withdrawn therefrom at the top and bottom of the chamber so that the water in effect acts as a piston within the chambers formed by the pockets 5. This results in drawing the fluid, gas or liquid which is to be pumped into the pockets 5 through the openings 12 and expelling it under pressure through the ports 16 to the compressor outlet. The movement of the liquid within the casing 7 relative to the interior wall thereof results in a considerable frictional loss when operated at high speeds. To lessen this frictional loss, there is disposed within the chamber 7 a continuous flexible band 17 of substantially the width of the chamber and with the length of the band only slightly less than the length of the interior surface of the chamber so that the band will assume a position closely adjacent the chamber wall. The band 17 is free floating and freely rotatable as it floats in the liquid medium. To lessen any tendency for local pressure differences causing contact between the band 17 and the inner wall of the casing 7, there are provided in the casing walls a pair of fluid ducts leading to the space between the band and the casing wall. These comprise cut out portions 18 in the side walls of the casing communicating with notches 19 in the inner surface of the casing and serve to maintain the band in a position spaced from the surface of the casing. While a single band 17 has been shown in the drawing, it is understood that a plurality of such bands of lessening peripheral length may be used to secure a still greater reduction in the frictional loss.

With the use of a single band as shown in Figures 1 through 5, it has been found that the band 17 will rotate at a speed about one-half the speed of rotation of the rotor 1 and that the frictional resistance with respect to the inner surface of the casing 7 adjacent which the band rests is reduced to substantially one-fourth that occurring without the band since the frictional loss varies substantially as the square of the speed. These figures, of course, do not take into account variations which may occur due to local turbulences in the liquid. Also, since the rotating liquid is in contact with the side walls of the chamber formed by the casing 7, the overall frictional loss due to the contact of the fluid

with the casing walls is not reduced to the one-fourth which is effected only at the inner peripheral surface of the casing.

Where, in the appended claims, the introduction "In a device of the class described" is utilized, it is intended to cover any apparatus in which a solid surface and a fluid medium contacting the same are relatively movable.

While a preferred embodiment of the invention has been specifically disclosed, it is understood that the invention is not limited thereto, as many variations will be readily apparent to those skilled in the art and the invention is to be given its broadest possible interpretation within the terms of the following claims.

What is claimed is:

1. In a device of the class described, a casing having a continuous curved inner peripheral surface; a fluid in said casing; means for causing relative rotative movement between said casing and fluid; and means for reducing the frictional loss sustained by said fluid at said surface, said means comprising a continuous imperforate endless band of uniform cross section disposed within said casing in said fluid closely adjacent to said surface, said band having an outer circumference smaller than the inner peripheral length of said surface, the band thus being adapted to float in said fluid out of mechanical contact with said surface, said band being spaced from rotating mechanical parts and having freedom to rotate with respect to said casing by fluid friction drag exerted upon it by said fluid; and means in said casing for equalizing the fluid pressure on opposite surfaces of said band, whereby the band is relieved from fluid pressure acting on its interior surface.

2. In a device of the class described, a casing of elliptical cross-section; a fluid in said casing; means for revolving said fluid relative to said casing; and means for reducing the frictional loss sustained by said fluid at said casing wall comprising a flexible endless imperforate band of uniform cross section disposed in said casing in said fluid with the surface of the band immediately adjacent to and parallel to the surface of the casing, said band having an outer circumference smaller than the inner peripheral length of said surface, the band thus being adapted to float in said fluid out of mechanical contact with said

surface, said band being spaced from rotating mechanical parts and having freedom to rotate with respect to said casing by fluid drag exerted upon it by said fluid, said band by reason of its flexibility following the elliptical contour of said casing; and a duct in said casing for equalizing the fluid pressure on opposite surfaces of said band, whereby the band is relieved from one sided fluid pressure in its passage through fluid portions of greater and less pressure.

3. In a device of the class described, a casing having a continuous curved inner peripheral surface; a fluid in said casing; means for causing relative rotative movement between said casing and fluid; and means for reducing the frictional loss sustained by said fluid at said surface, said means comprising an endless flexible imperforate band of uniform cross section disposed within said casing in said fluid closely adjacent to said surface, said band having a length sufficiently less than the length of the said surface so as to be disposed out of contact but immediately adjacent to said surface, said band being spaced from frictional contact with rotating mechanical parts and being adapted to move relatively to said casing solely by fluid drag exerted upon it by said fluid; and a duct in said casing for equalizing the fluid pressure on opposite surfaces of said band for relief of said band from one-sided fluid pressure.
